UNITED STATES PATENT OFFICE.

THOMAS ALFRED CHARLES COOK, OF CHICAGO, ILLINOIS.

SUPPORT AND SHIELD FOR FLATIRONS.

Application filed March 6, 1925. Serial No. 13,627.

To all whom it may concern:

Be it known that I, THOMAS ALFRED CHARLES COOK, a citizen of the United States, and a resident of Chicago, in the county of Cook and State of Illinois, have invented a new and useful Improvement in Supports and Shields for Flatirons, of which the following is a full, clear, and exact description.

10 My invention relates to improvements in combined support and shield for flatirons, and it consists in the combinations, constructions and arrangements herein described and claimed.

15 An object of my invention is to provide a device of the character described in which means is provided for supporting a flatiron in an inverted position with the work engaging surface in a horizontal plane so that 20 the iron may be employed for steaming, as by placing a dampened pad upon the work engaging surface and drawing fabric to be steamed thereover. At the present time special devices must be employed for steaming fabrics, since the ordinary flatiron cannot be placed in an inverted position without falling over.

25 A further object of my invention is to provide a device of the character described for entirely encasing the flatiron when not in use and for supporting the iron with its work engaging surface slightly above the lower wall of the case so that the case may be placed upon a supporting surface, such 30 as a shelf or the like, without any danger 35 of fire through conduction of heat from the iron, or without danger of damage to varnished surfaces or the like upon which the case is placed.

40 A further object of my invention is to provide a device of the character described which is adapted for use with any type of flatiron, whether it be electric, gas or a sad-iron.

45 A further object of my invention is to provide a device of the character described which is simple in construction, durable and which is thoroughly practical for the purpose intended.

50 Other objects and advantages will appear in the following specification, and the novel features of the invention will be particularly pointed out in the appended claim.

55 My invention is illustrated in the accompanying drawings forming part of this application, in which

Figure 1 is a front elevation of an embodiment of my invention with the iron in operative position,

Figure 2 is a sectional view along the 60 line 2—2 of Figure 1 with the iron in an inoperative position, and

Figure 3 is a perspective view of a modified form of my invention.

In carrying out my invention I make use 65 of a body member A having a horizontal base portion 2 supported upon four rubber legs 3. The cross sectional contour of the body member A is clearly shown in Figure 1 of the drawing and has tapering side walls 70 which terminate in inwardly extending top walls 5 parallel with the bottom wall 2. The top walls 5 are inclined toward the center of the body member A as shown at 6 and terminate in substantially vertical 75 parallel gripping members 7. The distance between the gripping members 7 is less than the diameter of the handle portion 8 of the flatiron, such as shown at 9.

Thus the flatiron 9 may be suspended with- 80 in the body member A in the position shown in Figure 2 with the handle 8 resting partially between the inclined portions 6 of the body, and partially above the top wall 5 with the work engaging surface 10 of the 85 iron above and entirely out of engagement with the bottom wall 2 of the body member. The flatiron is disposed in this position when not intended for use.

Means for entirely enclosing the flatiron 90 when in the position shown in Figure 2 con- 95 sists in a rear wall 11 which extends upwardly from the bottom 2 to the point of merger between the inclined surface 6 and the parallel portions 7 of the body member. 95 The wall 11 is secured to the edges of the parallel portions 7 by the projection of lugs 12 extending from the edges through the wall 11 and clinched over in a manner well known in the sheet metal art, so as to se- 100 curely hold the wall 11 in the position shown in Figure 2. The contour of the rear wall 11 conforms precisely to the contour of the body member as shown in Figure 1, i. e., its edges conform with the inclination of the 105 side walls 4.

A movable plate 13 is hingedly mounted at 14 to the upper edge of the rear wall 11 and extends slightly above the top walls 5 of the body member. A movable cover 110 plate 15 is hingedly mounted at 16 to the plate 13 and extends entirely across the top

of the body member to the front edge thereof where it is hingedly connected at 17 to a movable front cover plate 18.

This front plate 18 has an opening 19 therethrough adjacent to the lower edge through which a spring catch 20 secured at 21 to the bottom wall 2 of the device is permitted to project and thus engage with the plate 18 so as to hold the plate 10 yieldingly in place.

The cover plates 13, 15 and 18 are shown in closed position in Figure 2 and as they would be when the iron 9 is out of use. Thus the iron is fully encased and protected from accidental contact with the combustible or perishable material and objects, and with its work engaging surface 10, which is usually hot when the iron is put away, entirely out of contact with any part 29 of the casing.

When the iron is in use, as for steaming, and inverted (as shown in Figure 1) with the work engaging surface 10 in engagement with the top walls 5, the cover plates 13, 15 and 18 are hinged back and lie at the rear of the device. These plates cannot be seen from the position shown in Figure 1, since the contour of the plates conforms precisely with the contour of the adjacent parts of 30 the body member when closed. The side walls 4 have parallel portions 4^a which are corrugated to further reinforce the body member.

From the foregoing description of the various parts of the device the operation thereof may be readily understood. The use of a flatiron, whether it be electric, gas or of the sadiron type, for steaming goods is well known, and it has been found to be quite efficient for household use. Up to the present time, however, no mechanism has been provided for permitting the use of the iron for steaming with convenience. My improved support and shield for flat- 45 irons provides a device, when the plates 13, 15 and 18 are hinged back out of engagement with the casing which is an ample and substantially rigid support for the flatiron, with its work engaging surface 10 in the 50 position shown in Figure 1 and in the proper position for steaming fabrics. This steaming operation is performed usually by placing a wet pad directly upon the iron and moving fabrics thereover. Thus such 55 fabrics as velvet and the like may be neatly pressed.

When the flatiron is not in use, either for

steaming or for pressing, it is disposed in the position shown in Figure 2, the handle portion 8 being above the parallel members 6 7 and thus held with its work engaging surface 10 entirely free of any part of the casing, particularly the bottom 2. The cover plates 13, 15 and 18 are then moved to the position shown in Figure 2 and the plate 6 18 engaged with the latch member 20 by projection of that member through the opening 19. The entire casing and support bearing the iron may then be placed upon a varnished shelf or near combustible materials without any danger thereto, and with the iron fully protected from abuse.

In Figure 3 I have shown a modified form of my invention which is intended to be constructed at small cost. In this device no 75 cover plates nor rear plate are employed, and the body member A is constructed entirely of substantially rigid wire rods. This modified form bears reference numerals corresponding to the corresponding parts in the 80 preferred form. The only difference in construction between the body member proper in the preferred form and modified form is that the modified form is entirely constructed of rigid wire and has no back wall 85 or cover plates, but has connecting links 25 for preventing undue separation of the portions of the device corresponding with the parallel walls 7 in the preferred form. Also there are no legs 3 provided in the modified form. The operation of the modified form as to support of the flatiron in upright and inverted position is precisely the same as that of the preferred form. The 90 wire rods comprising the structure of the 95 modified form of my invention are welded together to secure the greatest possible rigidity.

I claim:

The combination with a flatiron having a 100 handle member, of a combined supporting member and shield comprising a casing and provided with a longitudinal slotted portion at the top wall thereof for yieldingly receiving the portion of the handle member 105 between the handle and the body of the iron, whereby the flatiron may be supported in an upright or inverted position at will, said casing being of sufficient height to maintain the bottom of the iron entirely out 110 of engagement with the adjacent portions of the supporting member and shield when the iron is in an upright position.

THOMAS ALFRED CHARLES COOK.
